UNITED STATES PATENT OFFICE.

GEORGE F. WEBB, OF HAMILTON, ONTARIO, CANADA.

PROCESS OF MANUFACTURING TIPLESS INCANDESCENT LAMPS.

Application filed April 14, 1927, Serial No. 183,795, and in Canada April 23, 1926.

This invention relates to improvements in the process of manufacturing the stem bodies of tipless incandescent lamps, and more particularly to an improved method 5 of uniting the exhaust tube of glass to the homogeneous leading-in tube.

The invention further relates to an improvement in the process disclosed in my Patent No. 1,580,226 of April 13th, 1926. 10 The process described in this patent relates to a method of uniting the exhaust tube with the leading-in tube during the step of uniting the filament stem with the latter mentioned tube, and consists of axially aligning 15 the filament stem and exhaust tube with their adjacent ends within the leading-in tube, fusing to plasticity and producing masses coalescence of the end of the filament stem and the proximal portion of the leading-in tube, thereby causing the end of the 20 exhaust tube to bend toward the walling of the leading-in tube by thermo-attraction and become welded to said walling adjacent the mass, then introducing a current into the exhaust tube from its outer end and blowing 25 an opening in the junction part of the two tubes.

Due sometimes to imperfection in the exhaust tube, or an inequality or inadequacy of 30 material, or imperfect adjustment in setting up the parts, the exhaust tube would fail to properly weld to the leading-in tube, with the resultant waste of all the parts.

The important object of the present invention, therefore, is to provide means for assuring the proper operative union of the exhaust tube and leading-in tube, and the invention consists essentially of utilizing an 35 exhaust tube provided with an enlarged hollow globular body on that end of the same which is to be welded to the leading-in tube, or, producing such an enlarged portion during the process of making the lamp.

Now it appears that the production of the 40 enlarged globular portion or body on the end of the exhaust tube necessitates an additional step in the process of manufacturing the lamps, and prolongs and involves the process, but, the material conserved thereby fully 45 warrants the more intricate procedure.

The object of the invention, then, may be attained in the manner which will be hereinafter more particularly described, illustrated in the accompanying drawing, and ascertained in the claims hereunto annexed. 55

Referring to the drawing:

Figure 1 is an elevation of an exhaust tube prior to its being treated and connected or united to the leading-in tube;

Figure 2 is an elevation of the exhaust 60 tube as being in course of subjection to a plastic homogenous foreign body in accordance with this invention;

Figure 3 is an elevation of the exhaust 65 tube as having acquired a portion of the foreign body of glass in the form of a glass node;

Figure 4 is an elevation of the exhaust tube showing the formation of the enlarged 70 hollow globular body thereon;

Figure 5 is a sectional elevation of the exhaust tube, leading-in tube, filament stem, the lead wires, in position as in preparation for coalescence by application of heat;

Figure 6 is a sectional elevation of the 75 stem body comprised of the units characterized in the description of Figure 5 subsequent to the consummation of coalescence; and,

Figure 7 is an elevation of the structure 80 shown in Figure 6 as seen as having been given a quarter revolution on its axis.

Similar reference characters refer to corresponding parts throughout the several views.

The exhaust tube is designated on the drawing by the numeral 12, the leading-in tube by 13, the filament stem by 14, and the lead wires by 15. These latter have no part in the present invention and are shown 90 merely because they form part of the stem body, and are embodied therein in the well known usual manner.

The important feature of the invention is the enlarged hollow globular body on the inner end of the exhaust tube 12 before said tube is united to the leading-in tube 13. This exhaust tube comprises a length of tubular glass as shown in Figure 1, and the end of which is later to be welded to the 100

leading-in tube 13, is subjected to an application of heat which reduces this part of the glass tube to plasticity and seals the end of the tube, and while it is thus plastic it is, by direct contact, applied momentarily to a glass mass 16 which is in a like plastic state. The object of this application is to annex to the end of the exhaust tube by capillary attraction and molecular adhesion 10 some of the glass from the mass 16 and thus produce temporarily a node 17 of massed glass upon said end, as in Figure 3. In this manner the end of the tube is supplemented in material.

15 Immediately subsequent to the production of the node 17, and before it chills, a gentle current of air or the like is applied to the opposite or open end of the tube, as from the nozzle 18 for example. This current enters 20 the core of the tube, expanding the node 17 to form the enlarged hollow globular body 19, as in Figure 4. The exhaust tube is now prepared for welding to the leading-in tube 13.

25 In completing the process of forming the stem body, the exhaust tube 12 is inserted within the leading-in tube 13 from the flared end of the latter mentioned tube, and the filament stem 14 is inserted from the opposite end of the leading-in tube in axial alignment with the exhaust tube, but spaced from the globular body 19, as in Figure 5; and the lead wires 15 are also positioned. Heat 30 is now applied to the end of the leading-in tube 13 and the proximal end of the filament stem; and when fused these parts coalesce and are subsequently pressed together in a flat mass 20 by a suitable clamping device. During this fusion and coalescence of the 35 leading-in tube and filament stem, the proximal portion of the walling of the leading-in tube and the enlarged globular body 19, which are very close together, as will be noted, become semi-molten or plastic, and the 40 latter by thermo-attraction yields to the walling of the leading-in tube and adheres thereto. As the said body 19 is thus welded to the walling of the leading-in tube, before the parts chill, a comparatively strong current 45 of air or the like is introduced to the outer open end of the exhaust tube, and the current thus introduced blows out the film of plastic glass which theretofore closed the welded end of said tube and the registering 50 portion of the walling of the leading-in tube. This establishes the objective communication from the exterior of the leading-in tube to the interior of the exhaust tube at 21, as in Figures 6 and 7. These figures show the 55 completed stem body.

60 I claim:

1. The method of assembling the stem body of incandescent lamps comprising leading-in tube, exhaust tube, filament stem, and lead wires, which consists of forming an enlarged hollow globular body on one end of the exhaust tube, inserting within the leading-in tube that end part of the exhaust tube having said globular body, inserting one end part of the filament stem within the leading-in tube from the opposite end thereof, placing the lead wires, fusing to plasticity and producing massed coalescence of the end part of the filament stem and the proximal portion of the leading-in tube, thereby also inducing said globular body, by thermo-attraction, to yield to the nearest portion of the walling of the leading-in tube and by molecular adhesion to weld itself thereto adjacent the mass formed aforesaid, and then introducing a current into the exhaust tube from its outer end while the material at the junction of said tubes is yet plastic, thereby blowing an opening at said junction to establish an objective communication from outside the leading-in tube to inside the exhaust tube.

2. The method of assembling the stem body of incandescent lamps, which consists of inserting within a leading-in tube an exhaust tube having an enlarged hollow globular body on the end entering the leading-in tube, inserting one end part of a filament stem within the leading-in tube from the opposite end thereof, placing lead wires, fusing to plasticity and producing massed coalescence of the end part of the filament stem and the proximal portion of the leading-in tube, thereby also inducing said globular body, by thermo-attraction, to yield to the nearest portion of the walling of the leading-in tube and by molecular adhesion to weld itself thereto adjacent the mass formed aforesaid, and then introducing a current into the exhaust tube from its outer end while the material at the junction of said tubes is yet plastic, thereby blowing an opening at said junction to establish an objective communication from outside the leading-in tube to inside the exhaust tube.

3. The method of assembling the stem body of incandescent lamps comprising leading-in tube, exhaust tube, filament stem, and lead wires, which consists of fusing to plasticity and sealing one end of the exhaust tube, supplementing the sealed end of the exhaust tube by the annexation of homogeneous material thereby forming a node thereon, expanding the node by introducing a current into the exhaust tube and thereby forming an enlarged hollow globular body, inserting within the leading-in tube that end part of the exhaust tube having said globular body, inserting one end part of the filament stem within the leading-in tube from the opposite end thereof, placing the lead wires, fusing to plasticity and producing massed coalescence of the end part of the filament stem and the proximal portion of the leading-in tube, thereby also inducing said

globular body, by thermo-attraction, to yield to the nearest portion of the walling of the leading-in tube and by molecular adhesion to weld itself thereto adjacent the mass formed 5 aforesaid, and then introducing a current into the exhaust tube from its outer end while the material at the junction of said

tubes is yet plastic, thereby blowing an opening at said junction to establish an objective communication from outside the leading-in 10 tube to inside the exhaust tube.

In testimony whereof he has affixed his signature.

GEORGE F. WEBB.
